DESIGN FOR A BABY RATTLE

Edward T. Fretz, Sherman Oaks, Calif., assignor to Aard Company, Los Angeles, Calif., a co-partnership

Application March 13, 1945, Serial No. 118,462

Term of patent 7 years

(Cl. D34—15)

To all whom it may concern:

Be it known that I, Edward T. Fretz, a citizen of the United States, residing at Sherman Oaks, in the county of Los Angeles and State of California, have invented a new, original, and ornamental Design for a Baby Rattle, of which the following is a specification, reference being had to the accompanying drawing, forming a part thereof.

Fig. 1 is a perspective view of a baby rattle showing my new design; and

Fig. 2 is a vertical cross sectional view of the same taken along line II—II of Fig. 1.

I claim:

The ornamental design for a baby rattle, as shown.

EDWARD T. FRETZ.
